UNITED STATES PATENT OFFICE

94,847

DESIGN FOR AN AUTOMOBILE

James V. Martin, Garden City, N. Y.

Application December 18, 1933, Serial No. 50,102

Term of patent 14 years

To all whom it may concern:

Be it known that I, James V. Martin, a citizen of the United States, residing at Garden City, Nassau County, in the State of New York, have invented a new, original, and ornamental Design for Automobiles, of which the following is a specification, reference being had to the accompanying drawing forming part hereof.

Fig. 1 is a view in side elevation showing the automobile of my design.

Fig. 2 is a top plan view of the same automobile design.

In my ornamental automobile design, the lower portion of the automobile body together with a guard strip is the dominant feature of the design.

I claim:

The ornamental design for an automobile as shown and described.

JAMES V. MARTIN.
